UNITED STATES PATENT OFFICE.

ISAAC KIRSCHENBAUM, OF NEW BRUNSWICK, NEW JERSEY.

STEAMING BRUSH.

Application filed January 11, 1927. Serial No. 160,439.

This invention relates to brushes employed in clothing or tailoring establishments for brushing the cloth or garments and comprehends means associated with the brush for projecting jets of steam through the bristles and onto the surface being brushed.

At the present time it is the common practice to project onto the surface of the cloth or garments, a jet of steam and employ a separate brush for the brushing operation. This system or method has a number of disadvantages and objectionable features and in order to overcome the same the present invention aims to provide a combined brush and steaming apparatus whereby the steaming and brushing operations are greatly facilitated.

The invention furthermore comprehends a steaming brush provided with means for preventing an excessive wetting of the cloth or garments by removing and absorbing the water of condensation from the steam prior to its application to the surfaces being brushed.

Other objects reside in the simplicity of the construction, the economy with which the same may be produced and operated, and the general efficiency derived therefrom.

With the above recited and other objects in view, reference is had to the following specification and accompanying drawings in which there is exhibited certain examples or embodiments of the invention which are in no way intended as limitations upon the scope of the appended claims as it is to be clearly understood that variations and modifications which properly fall within the scope of said claims may be resorted to when found expedient.

In the drawings—

Figure 1 is a longitudinal sectional view through the steaming brush;

Fig. 2 is a transverse sectional view therethrough taken approximately on the line 2—2 of Fig. 1;

Fig. 3 is a sectional plan view taken approximately on the line 3—3 of Fig. 2.

Fig. 4 is a fragmentary detail view of a modified adaptation of the invention.

Referring to the drawings by characters of reference, 10 designates a brush head which is formed with a recess 11 on its under side and which may be provided with a manipulating handle 12 on its upper side.

55 A cover plate 13 is attached to the under

side which also constitutes a support for the bristles 14. A guard element 15 having a central opening 16 conforming substantially to the size and shape of the recess 11, is interposed between the cover plate 13 and the brush head 10, and is preferably of rubber or any other suitable material to serve as a gasket or sealing element between the confronting faces of the cover plate 13 and the brush head. The guard element is of a size 60 to project appreciably beyond the sides and ends of the brush head. A nozzle 17 extends through the brush head 10 and communicates with the recess 11 and said nozzle is provided with an offset outer end 18 which is connected with a flexible conduit 19, which conduit is in turn connected with a source of steam supply. Between the offset end 18 and the outlet end of the nozzle, an outlet pipe 20 depends and is connected with a condensate 65 conduit 21 which conduit is preferably bound to the steam conduit 19. The cover plate 13 is formed with a plurality of ports 22 which are adapted to discharge steam through the bristles from the base of the same. Within 70 the recess 11, a suitable absorbent material 23 is positioned to further assist in removing from the steam the water of condensation.

In use and operation, the steam supplied through the conduit 19 is prevented by the 85 offset 18 from directly entering the recess 11 so that water of condensation produced in the conduit 19 will be partially discharged through the outlet 20 into the condensate conduit 21. The condensate which is introduced into the recess 11, will be further partially absorbed by the absorbent material 23 so that the steam which is finally projected through the ports 22 and through the bristles onto the surface of the cloth being 90 brushed, will be fairly free of water of condensation in order to prevent an excessive wetting of the surface being brushed. The portion of the guard element 15 which extends beyond the side and end edges of the 100 brush head, will prevent live steam from contacting with and injuring the hand or arm of the operator.

In the modified form of the invention illustrated in Fig. 4, the nozzle 17 which is of 105 identically the same construction disclosed in the preferred form of the invention, is illustrated as equipped with a heating jacket 24 surrounding the nozzle between the offset outer end 18 and the inner end which 110

2
extends through the brush head. Within the jacket a suitable electric heating element is arranged which is supplied through conductor wires 25 with current for heating and assisting in the partial drying up or the condensate to prevent an excessive moisture being carried with the steam onto the face of the fabric being brushed.

From the foregoing it will thus be seen that a combined surface brushing and steaming device has been devised which greatly facilitates the steaming and brushing operations of cloth or garments.

What is claimed is:

- 15 1. A steaming brush, including a hollow brush head having bristles on one of its surfaces and ports extending through the bristle-supporting surface, a nozzle extending through the wall of the brush head and communicating with the interior, a steam conduit connected with the outer end of said nozzle, and a condensate drain pipe connected with said nozzle intermediate its ends, the said nozzle being formed with an offset 25 at a point between the condensate drain and its outer end for retarding the conveyance of condensate to the interior of the brush head by the force of the steam entering the same.

2. A steaming brush, including a hollow brush head having bristles on one of its surfaces and ports extending through the bristle-supporting surface, a nozzle extending through the wall of the brush head and communicating with the interior, a steam conduit connected with the outer end of said nozzle, a condensate drain pipe connected with said nozzle intermediate its ends, the said nozzle having an offset at a point between the condensate drain and its outer end 40 for retarding the conveyance of condensate to the interior of the brush head by the force of the steam entering the same, and absorbent means within the brush head for further removing condensate from the steam projected through the bristles.

3. A steaming brush, including a hollow brush head having openings communicating with the bristles, means for projecting jets of steam through said head and the bristles, said means including a steam conduit connected with the brush head, said steam conduit including a nozzle having a condensate draining means, and means surrounding the nozzle for heating the same to dry up a portion of the condensate for the purpose set forth.

ISAAC KIRSCHENBAUM.
